UNITED STATES PATENT OFFICE.

CALVIN JACKSON, OF PHILADELPHIA, PENNSYLVANIA.

DESIGN FOR A FILE-CLEANER.

SPECIFICATION forming part of Design No. 32,188, dated February 6, 1900.

Application filed May 26, 1899. Serial No. 718,447. Term of patent 7 years.

To all whom it may concern:

Be it known that I, CALVIN JACKSON, a citizen of the United States of America, and a resident of the city and county of Philadelphia, in the State of Pennsylvania, have invented a certain new and original Design for a File-Cleaner, of which the following is a specification.

My invention relates to a machine-shop tool especially designed for use in cleaning files of varying cut, the teeth of which are apt to become clogged in service by bits of metal which attach themselves firmly thereto.

As shown in the accompanying drawing, my

design consists, essentially, of a handle *a*, 15 from each end of which project oppositely-flaring blades or plates *b b' b' b*, the abutting shanks *c c* or *c' c'* of which unite with the handle *a*, as shown.

What I claim is—

The design for a file-cleaning tool substantially as shown and described.

Signed by me at Reading, Pennsylvania, this 23d day of May, 1899.

CALVIN JACKSON.
